UNITED STATES PATENT OFFICE.

FRANK WAGNER, OF NEW YORK, N. Y.

FLOOR-WORKING MACHINE.

1,388,983.

Specification of Letters Patent. Patented Aug. 30, 1921.

Application filed November 24, 1917. Serial No. 203,654.

To all whom it may concern:

Be it known that I, FRANK WAGNER, a citizen of the United States, residing at New York, in the county of New York and State of New York, have invented certain new and useful Improvements in Floor-Working Machines, of which the following is a specification.

This invention relates to floor polishers or cleaners and particularly to the type which embody a movable frame adapted to be pushed about the floor and carrying a motor for operating the mechanism of the device.

15 One of the objects of the invention is to produce a machine having improved means for effecting the adjustment and driving of the polishing drums or brushes. Among the other objects of the invention is to provide means for driving the drums so as to facilitate the moving of the machine across the floor and to facilitate the removal of any dust or dirt by pneumatic means which may be used in conjunction with or independently of the polishing drums.

In the drawing which illustrates the preferred embodiment of the invention, Figure 1 is a side elevation of a machine embodying the invention, certain parts being broken away or merely indicated by dotted lines; Fig. 2 is a plan; Fig. 3 is a longitudinal vertical section through the machine; Fig. 4 is a longitudinal section taken near the side of the machine; Fig. 5 is a side elevation and partial section illustrating details; Fig. 6 is a detailed view of one of the gear elements which may be swung to disengage the same from driving connection with the motor; Fig. 7 is a front elevation partly in section of the gear element shown in Fig. 6; Fig. 8 is a front elevation partly in section of one of the polishing drums and Fig. 9 is a modification of the drum.

The machine preferably comprises a portable frame 1, mounted on wheels 2 preferably having rubber tires 3 that prevent their marring the surface of the floor. The machine may be pushed about the floor by any suitable means, such as a handle 4. The polishing or cleaning is preferably effected through the medium of two drums 5 preferably supported adjustably. For this purpose these drums are preferably supported on adjustable supporting frames, each frame consisting of a pair of arms 6, 6 between which each drum is carried rotatably. The

drums may be in the form of cylinders with polishing surfaces, or "clothing" 7 (see Fig. 8), or they may be in the form of brushes (see Fig. 9) with bristles 8. In order to enable the different kinds of drums to be interchanged the shafts 9 are made removable and may be held in place by set screws 10.

In order to raise or withdraw the drums 5 from the floor I prefer to provide a chain 65 connected with the arms 6 and arranged so as to wind around the shaft of a ratchet 12 with which coöperates a pawl 13 preferably pressed by a spring 14. The pawl may be held released (see Fig. 5) to let the drums 70 down on the floor. The arms of both drums are connected in any suitable manner to effect their simultaneous movement, preferably through segments 15 which form tails or rear extensions on a pair of the drums 6. 75 The ratchet and pawl evidently afford means for adjustably supporting the drums. Yielding means, such as a spring 16, is preferably provided for pressing the drums toward the floor. 80

The arms 6 are preferably pivotally supported at the axles 17 and the drums are preferably driven through the pivotal connection by means of sprocket sleeves 18 and 19 which are loose on the axles 17 of the 85 wheels 2. I prefer to drive the drums in opposite directions so that their tractive efforts neutralize each other and hence do not tend to move the machine across the floor, and I also prefer to drive them so that 90 the side of each drum adjacent the floor moves inwardly toward the frame of the machine. For this purpose a driving chain 20 is provided which passes under one sprocket sleeve for example, sleeve 18, and over the 95 other sleeve 19, being guided in this way by a guide sprocket 21. Each sleeve 18 or 19 drives its corresponding drum through a sprocket chain 22. Evidently the chain 20 affords means for driving the drums 5 in 100 any position the arms 6 may assume.

I prefer to provide means such as a wing nut 23 and slot 24 for clamping the arms 6, 6 in any adjusted position desired.

In order to regulate the degree of slackness of the chain 20 I prefer to support the guide sprocket 21 on an adjustable bracket 25. The chain 20 is preferably driven by an electric motor 26, the driving pinion 27 of which drives the chain through a gear 28 110 carrying a driving sprocket 29 rigid with the gear 28. The motor 26 is preferably mount-

ed on the middle of the frame 1 and is supplied with current through an electric cable 30 supported on the handle 4 and which may be provided at its other end with a plug to fit in any standard electric light socket.

In order to clean up the floor I prefer to provide pneumatic means which may include a suction fan 31 having an intake or suction head 32 between the drums 5 and 10 having a discharge uptake 33 terminating in a goose neck 34 supporting a bonnet 35 beneath which a receptacle, such as a bag 36, may be attached.

The fan may be driven at a high speed 15 from the motor by a belt 37 passing over a pulley 38 on the fan shaft.

The fan may be driven at the same time as the drums 5 where the work is light and not consuming great power at the drums, but if 20 desired the machine may be used solely as a pneumatic cleaner by locking the drums 5 up above the floor and also preferably disconnecting the drive from the motor to the chain 20. For thus purpose the gear 28 25 and sprocket 29 are preferably mounted on a swinging plate 39 (Fig. 6) supported on a pin 40 on a fixed bracket 41. By loosening the bolt 42 in the arcuate slot 43 the gear 28 can be swung to its disengaged position.

The drums 5 (Fig. 8) may be of any construction desired for cutting, abrading or polishing the floor. For abrading the floor the clothing 7 on the drum preferably comprises a pad 7^a of felt and a covering 7^b of sandpaper or similar material. These clothing sheets may be conveniently attached to the drums by jamming the ends or edges of these sheets into a longitudinal slot 7^c 40 in the wall of the drum. And if desired a renovator of any well known form or suction head (not illustrated) for cleaning walls and furniture may be attached to a hose 44 (see Fig. 4). But normally the elbow connection 45 would be plugged.

It is understood that the embodiment of the invention set forth herein is only one of the many embodiments the invention may take, and I do not wish to be limited in the 50 practice of the invention nor in my claims to the particular embodiment set forth.

I claim:

1. In a floor polishing machine, the combination of a frame mounted on wheels, a pair of supporting arms pivotally carried thereby, a rotatable drum supported between said arms, means for adjusting said arms upwardly to withdraw said drum from the floor, yielding means tending to force the drum toward the floor, and means for driving said drum through the pivotal supports of said arms.

2. In a floor polishing machine, the combination of a frame mounted on wheels, a pair of arms projecting on opposite sides of said frame, a rotatable drum carried between each pair of arms, intermeshing means connecting the pairs of arms so that they move up or down in unison, means for raising said arms to withdraw said drums from the floor, means for yieldingly pressing said arms to force the drums toward the floor, a motor on said frame, and means for driving said drums from said motor.

3. In a floor polishing machine, the combination of a frame mounted on wheels, a pair of arms pivotally supported on opposite sides of said frame, a drum rotatably mounted between each pair of arms, segments connecting said pairs of arms to effect simultaneous up or down movement of said pairs of arms, a ratchet and pawl, a chain connected therewith and connected with said arms to raise the same, a spring tending to depress said arms to press said drums toward the floor, a motor on said frame and means for driving said drums from said motor.

4. In a floor polishing or cleaning machine, the combination of a frame mounted on wheels, a pair of polishing drums rotatably supported in said frame, a motor on said frame for driving said drums, a blower also driven by said motor having a suction intake between said drums, and means for disconnecting at will the driving connection from said motor to said polishing drums to permit the fan and suction intake to be operated independently of said drums.

In testimony whereof I affix my signature.

FRANK WAGNER.
